UNITED STATES PATENT OFFICE.

JAMES L. DROHEN, OF WASHINGTON, DISTRICT OF COLUMBIA.

AUTOMOBILE SIGNAL SWITCH.

Application filed November 7, 1923. Serial No. 678,838.

This invention relates to automobile signals, and more particularly to the means for operating the signals.

It is the purpose of this invention to provide a switch to control a plurality of electrically operated signals, in a manner whereby the signals can be selectively operated and to arrange the switch in a position with relation to the foot of the operator of the vehicle, so that the signals can be actuated by the heel of the operator.

Other objects and advantages of the invention will appear when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view in elevation of the foot operated switch.

Figure 2 is a view looking at the opposite side of Figure 1.

Figure 3 is a sectional view through the floor board of the vehicle showing the manner of maintaining the switch on one of the control pedals of the vehicle.

Figure 4 is a diagrammatic view.

Figure 5 is a fragmentary sectional view through the switch.

Figure 6 is a sectional view through one of the switch elements.

My improved switch is particularly adapted for use for controlling signals on motor vehicles which are generally indicated by numerals 10, 11, 12, 13 and 14 respectively. The switch includes a fixed contact 15 and a movable contact for each circuit, and these movable contacts are indicated at 17, 18, and 19 respectively.

The switch embodies a supporting plate or member 20 which includes an attaching portion 21, and the latter is adapted to be secured to one of the control pedals 22 of the vehicle in any suitable manner, such as for instance by means of fastening elements 23, the supporting member 20 consequently depending from the control pedal 22 and has its lower portion enlarged and slightly offset as shown in Figure 5. It is this portion of the supporting plate that carries the various switch mechanism, each of the movable switch elements being preferably in the nature of push buttons as illustrated. The

fixed contacts 15 above referred to are carried by a curved bar 24 which supports the binding post with which the various wires 25 of the supports are terminally connected. 60 Arranged upon one side of the supporting member 20 is a guard plate 26 having an area substantially equal to that of the lower portion of said supporting member and overlying the various push buttons or movable 65 switch elements 17, 18 and 19 respectively. This guard plate is slit at spaced points as at 27, and the separated portions provide resilient tongues. There is one of these tongues indicated at 28 for each movable 70 switch element, the tongue overlying said element and adapted to be depressed in order to actuate said element as will be readily understood. When the foot of the operator of the vehicle reposes upon the pedal 22, the 75 heel of the operator is arranged directly above the guard plate 26, and the heel can be shifted laterally into proper relation with any particular switch element, so that the latter can be actuated to close the circuit 80 to the signals to be operated. It will be noted upon inspection of Figure 3, that the guard plate 26 is further provided with yieldable or resilient tongues 29 which fill the space between the tongues 28 to provide 85 a smooth surface. Of course the heel of the operator can be shifted, and the tongues can be depressed with any one of the tongues 28 to close a particular circuit, and therefor provide a broader bearing surface for the 90 heel when it is desired to operate the signals. Obviously by reason of this construction and arrangement of parts, the driver of the vehicle can operate the right turn signals, or the left turn signals, or the stop signal as the 95 occasion may require by simply depressing the heel of the foot reposing upon the control pedal 22, and thus maintain both hands on the steering wheel of the vehicle and also give his undivided attention to the guidance 100 of the vehicle under all circumstances. It is of course to be understood that the various circuits can be closed by depressing the heel simultaneously with the operation of the clutch pedal 22, and independently of any 105 movement thereof.

While it is believed that from the foregoing description, the nature and advantages of the invention will be readily apparent, I desire to have it understood that I do not 110 limit myself to what is herein shown and described, and that such changes may be re-

sorted to when desired as fall within the scope of what is claimed.

Having thus described the invention, I claim:

- 5 A switch of the class described including a supporting plate, a transverse attaching portion at one end, an enlarged portion at the other end, a curved bar mounted upon the enlarged portion, a plurality of fixed contacts carried by the bar, a guard plate arranged over the enlarged portion, said

guard plate being slit transversely at spaced points to provide yieldable tongues, movable contacts carried by the bar and disposed beneath the tongues in opposed relation with the stationary contacts whereby inward pressure of the yieldable tongues will cause said yieldable contacts to be moved into engagement with a stationary contact as and for the purpose specified. 20

In testimony whereof I affix my signature. 25

JAMES L. DROHEN.
